(57) **CLAIM**

The ornamental design for an animal muzzle as shown and described.

DESCRIPTION

FIG. 1 is a perspective view of an animal muzzle showing my new design.

FIG. 2 is a front view thereof.

FIG. 3 is a rear view thereof.

FIG. 4 is a right side view thereof.

FIG. 5 is a left side thereof.

FIG. 6 is a top view thereof; and,

FIG. 7 is a bottom view thereof.

The broken lines in FIGS. 1-7 show portions of the animal muzzle that form no part of the claimed design of the invention.

1 Claim, 7 Drawing Sheets
